(57) **CLAIM**

We claim, the ornamental design for a syringe device, as shown and described.

DESCRIPTION

FIG. 1 is a top perspective view of a syringe device;

FIG. 2 is a front elevational view of the syringe device of FIG. 1;

FIG. 3 is a bottom perspective view of the syringe device of FIG. 1;

FIG. 4 is a top view of the syringe device of FIG. 1;

FIG. 5 is a right side elevational view of the syringe device of FIG. 1;

FIG. 6 is a left side elevational view of the syringe device of FIG. 1;

FIG. 7 is a rear elevational view of the syringe device of FIG. 1;

FIG. 8 is a bottom plan view of the syringe device of FIG. 1; and,

FIG. 9 is a side view in cross section of the syringe device of FIG. 1 taken along line 9-9 of FIG. 4.

The broken lines in the drawings illustrate portions of the syringe device and form no part of the claimed design.

1 Claim, 5 Drawing Sheets
